UNITED STATES PATENT OFFICE.

FRANK E. SHARP, OF CORNING, NEW YORK, ASSIGNOR OF ONE-HALF TO G. EDWIN THOMAS,
OF CORNING, NEW YORK.

HOSE-SUPPORTER.

No. 868,584.

Specification of Letters Patent.

Patented Oct. 15, 1907.

Application filed February 26, 1907. Serial No. 359,474.

To all whom it may concern:

Be it known that I, FRANK E. SHARP, a citizen of the United States, residing at Corning, in the county of Steuben and State of New York, have invented certain new and useful Improvements in Hose-Supporters; and I do hereby declare the following to be a full, clear, and exact description of the invention, such as will enable others skilled in the art to which it appertains to make and use the same.

- 10 My invention relates to new and useful improvements in supporters and more particularly to that class adapted to be used for supporting hosiery, and my object is to provide means for securing the upper end of the supporter to the garment of the wearer.
- 15 A further object is to provide means for adjusting the length of the supporter, and a still further object is to provide means for securing elastics to the supporter proper whereby the length of the supporter may be adjusted without changing the tension of the elastic.
- 20 Other objects and advantages will be hereinafter referred to and more particularly pointed out in the claims.

In the accompanying drawings which are made a part of this specification, Figure 1 is a perspective view 25 of my improved supporter complete; Fig. 2 is a sectional view of the upper end of the supporter showing one means of attaching the same to the garment, and, Fig. 3 is a detail perspective view of the upper end of the supporter.

30 Referring to the drawings in which similar reference numerals designate corresponding parts throughout the several views, 1 indicates the body of my improved supporter which is preferably constructed of a strip of non-elastic webbing, to one end of which is secured 35 the usual form of buckle or clasp 2 while the opposite end thereof is disposed through a clevis 3 and folded back upon itself, and the extreme free end thereof is directed through the buckle and held into engagement therewith in the usual manner.

40 The arms of the clevis 3 are provided with eyes 4 which extend around one bar 5 of a securing pin 6. The bar 5 is provided with a loop 7 at the central portion thereof which is adapted to engage a button 8 on a garment 9 and by which means the supporter is 45 secured to the garment. The stems 10 of the loop are directed substantially together so that the space between the stems is less than the space in the loop proper, so that when the loop is directed over a button or the like the stem portions of the loop are impinged against the stem or other securing means of the button, and prevent the loop from casual removal from the button.

One end of the bar 5 is curved upon itself to form a

coil spring 11, the free end of the spring terminating in a pin proper 12 which is parallel with the bar 5 and 55 spaced a suitable distance therefrom, the extreme free end of the pin being pointed so that it can be readily inserted through portions of the garment when desired and normally rests in a keeper 13 carried by the opposite end of the bar 5. It will thus be seen that 60 when there is no button upon the garment the pin 12 may be employed for securing the supporter to the garment, and while I have shown and described the loop as engaging a button it will be readily understood that other means may be employed for securing 65 the loop to the garment such as the usual form of hook or the like (not shown).

The arms of the clevis 3 are directed inwardly so that the eyes 4 are in juxtaposition to the base of the stems 10, the arms being so arranged that the eyes will 70 be held against the stems 10 under pressure thereby holding said stems from casually spreading and in order to prevent the arms of the clevis 3 from moving away from the base of the stems 10, I have provided 75 curved portions 14 in the bar 5 against which the eyes 76 4 rest, so that the arms of the clevis will be limited in their outward movement.

By the above construction it will be seen that I have embodied within the one article two separate and distinct means for securing the same to the garment, and 80 when the loop is employed to secure the supporter to the garment the pin will assume the position shown in Figs. 1 and 2 of the drawing, while when the pin proper is employed for securing the supporter to the garment the pin will assume the position shown in 85 Fig. 3 of the drawing.

Secured to the lower edge of the buckle 2 is a strap 15 which is provided at its free end with a socket 16 which is adapted to coöperate with a head 16' carried by the lower end of an auxiliary strap 17, said auxiliary strap being likewise secured to the buckle. The strap 15 is disposed around an elastic cord 18 to the free ends of which are secured clasps 19 of any preferred form and by which means the supporter is secured to the hose.

90 It will be seen that by making the cord 18 of elastic material the body 1 may be readily lengthened or shortened without affecting the elasticity of the supporter; and it will be further seen that the cord 18 may be readily disengaged from the body of the supporter 95 by releasing the socket 16 from its head 16'.

100 By this construction it will be seen that I can readily and quickly secure the supporter to the garment, and it is my intention to principally use the loop for this purpose, but should the button or hook become 105 disengaged from the garment then the supporter may

be secured in position by means of the pin 12, but said pin is not intended to be used except in cases where the securing means for the loop is missing.

What I claim is:

5. 1. In a supporter, the combination with a body portion and means to secure the same to hosiery; of a clevis at the upper end of said body, a securing pin carried by said clevis comprising parallel bars, a loop at the central portion of one of said bars, curved portions in the bar containing the loop whereby the outward movement of the clevis is limited, one of said bars being pointed at its end and forming a pin, a keeper for the pointed end of said pin, and a coil spring connecting said pin and bar.
- 10 2. In a supporter of the class described the combination with a body portion formed of non-elastic material; of a buckle, fixed to one end of said body adapted to engage the opposite end thereof, a strap fixed to said buckle, an auxiliary strap secured to the buckle, means to removably secure said straps together, an elastic cord engaged by the 15 first mentioned strap, clasps at the free ends of said elastic

cord adapted to secure the body to hosiery, a clevis engaged by said body, the arms of said clevis being directed inwardly and means carried by said clevis to secure said body to a garment.

3. The herein described means for securing a supporter 25 to a garment comprising a securing pin formed of a continuous section of material and having parallel sections, one section having a loop at its central portion while the opposite section is pointed to form a pin, a coil spring interposed between and connecting said sections, and a 30 keeper at the opposite end of said sections, a clevis having eyes to engage the section having the loop, the arms of said clevis being inwardly directed and curved portions in said section to keep the eyes in engagement with the base of the loop.

In testimony whereof I have signed my name to this specification in the presence of two subscribing witnesses.

FRANK E. SHARP.
